(74) Attorney, Agent, or Firm — Pierce Atwood LLP;
Kevin M. Farrell; David J. Wilson(57) **CLAIM**

The ornamental design for a face mask, as shown and described.

DESCRIPTION

FIG. 1 is a front view of a face mask showing our new design;

FIG. 2 is a rear view of the face mask;

FIG. 3 is a top view of the face mask;

FIG. 4 is a bottom view of the face mask;

FIG. 5 is a right side view of the face mask;

FIG. 6 is a left side view of the face mask;

FIG. 7 is a perspective view of the face mask; and,

FIG. 8 is an exploded perspective view of the face mask. The broken line showing of the headgear in FIG. 7 illustrates environment and forms no part of the claimed design. All other broken lines illustrate portions of the face mask that form no part of the claimed design.

1 Claim, 6 Drawing Sheets(56)
